INVENTOR

James M. Trier

By his Attorney *Ernest M. Mendenhall*

UNITED STATES PATENT OFFICE.

JAMES M. TRIER, OF NEW YORK, N. Y.

OFFSET-WEB CLEANER FOR PRINTING PRESSES.

Application filed November 25, 1927. Serial No. 235,497.

The present invention relates more particularly to improvements in the construction and arrangement of the cleaner set forth and claimed in Patent No. 1,287,524, issued to me under date of December 10, 1918, and has among its principal objects to avoid the particles being carried past the cleaner; to provide a rigid adjustment for the cleaner; and to simplify and strengthen the construction.

Figure 1 is a longitudinal vertical section showing, diagrammatically, the arrangement of printing, packing, and web-winding cylinders and guide rollers connected therewith as embodied in presses of conventional make together with a cleaner for the web constructed and arranged in accordance with the present invention.

Figure 2 is a top plan view of the cleaner. Figure 3 is a cross section of the cleaner frame showing the arrangement of the adjusting means therefor, the section being taken as on the line 3-3 in Figure 2.

Figure 4 is a cross section of the cleaner frame showing in connection therewith a fragment of the web, the parts being shown on enlarged scale and the section being taken as on the line 4-4 in Figure 2.

A disadvantage in the use of the cleaner disclosed in the prior patent above referred to has been found to be that the ink and inking particles picked up by the web, when in contact with the printing sheet, will later accumulate on the cleaner blades until the accumulation encroaches upon and raises the web at the blade sufficiently to be carried over toward the web roller.

It has been found that the successive blades attempt to clean the web and to arrest these particles which may be carried by the preceding blade. When, as heretofore, the final blade is passed with the blade in contact with the web, the same effect is produced on the final blade with the result that accumulated bits pass over the blade adhering to the blade to become later rolled between layers thereof when the web is finally rewound upon the web roll.

A further defect in the operation of the previous cleaner has been found to be that the frame has a tendency to rock in sympathy with the roll or run of the web incident to the fact that the stress or strain on the web alternates from side edge to side edge thereof. With these two objections in mind, the present invention principally concerns the provision of a blade 9 which is mounted at the

rear edge of the cleaner frame 10 and in the rear of the cleaning blades 11 and 12.

As is best seen in Figure 4 of the drawings, the blade 9 is shortened so that a clearance is established between the upper edge of the blade 9 and the web 13. It will also be noted that the bridge bars 14 with which the frame 10 is supplied are slightly bowed upwardly or crowned so that the center of the cleaner is higher than at the front and rear edges thereof to extend above a straight line drawn between the guide rollers 15 with which the printing press is provided. The tension on the web 13 imposed by this construction is varied by adjusting the frame 10 up and down and to this end the frame 10 is provided with hanging brackets 16. The brackets 16 are suitably mounted on the frame 17 of a printing press by means of bolts 18 which extend through slots 19 in the brackets 16. It will be noted that the bolts 18 are disposed in staggered relation each to the other. This arrangement provides against any tendency to rock the brackets 16 and the cleaner frame 10 connected therewith.

The cleaner frame 10 is preferably mounted on the brackets 16, a rivet 20 serving as the pivot on which the frame may be swung. A bolt 21 mounted in a quadrant slot 22 is used to set the frame after it has been adjusted in the proper relation to the web and to the brackets 16.

In Figure 2 of the drawings it is best shown that the forward cleaning blades 12 are pivoted toward the front of the frame 10, the sides falling away to produce a lateral scraping effect on the web as the same is drawn thereover. The blades 11 are preferably straight, these blades being intended to serve as auxiliary or cleaning blades for the web after the same has passed the blades 12. It is to the rear of the blades 11 that the blade 9 is disposed.

With an apparatus constructed and arranged as herein disclosed the operation is as follows:

While printing on the sheet A between the type roller B and the pressure roller C, the web 13 is fed over from the web roller D through the guide rollers 15 to the winding roller E. The web 13 is especially useful where the printing is being done on both sides of the sheet A, therefore, the wet side of the sheet is rolled over the web 13 which travels at the same rate of speed without drag upon the sheet A. The roller C is thus protected

from becoming smeared and dirty. When the sheet has been run through, the web 13 is immediately rewound on the web roller D. It is at this time that the cleaner herein described functions. As the web is rewound it is drawn over the blades 12, 11 and past the blade 9 successively and in the order named. The tension on the web 13 incident to the elevation of the frame 10 and the blades thereon is such that the ink imparted to the web 13 by the sheet A, together with small particles of dust or other material natural to the atmosphere of a working press room is removed by the blades 12 and 11.

15 As above stated, the ink and other material thus arrested by the blades, piles up on the blades and consequently crowd over. When in time the accumulation of the last of the blades 11 acts in this way, the blade 9 not being in contact with the web 13 serves to knock the fragment hanging to the web therefrom without receiving the pressure that it would receive if it was in contact with the web. The attachment, if any, thus imparted to the ink-ing particle is not sufficient to make it adhere to the blade 9. The consequence of such is that it falls through the frame 10 and is lost sight of as far as this operation is concerned.

20 The result of the above described action is that the web when rewound on the web roll D has been denuded of the ink and particles which otherwise would become embedded in

the roll with the result that when the web was again used the accumulation or spot would be transferred to the sheet A.

35 It will be noted also that if in the operation of the web, or if by any inequality in the tensile strength of the paper forming the web, one or other of the side of the web has stretched, the rigid frame with the rigid 40 blades 11 and 12 will correct the stretch of the web so that it returns to the roll D in proper condition for re-use.

What I claim is:

1. In combination with a printing press 45 having an offset web and equipment relating thereto, of a cleaner comprising a plurality of scraper blades adapted to frictionally engage said web, and a guard blade disposed between said scraper blade and the roller for 50 said web, said guard blade being adjacent to but out of contact with said web.

2. In combination with a printing press having an offset web and equipment relating thereto, of a cleaner comprising a plurality 55 of scraper blades adapted to frictionally engage said web, and a guard blade disposed between said scraper blade and the roller for said web, said guard blade being adjacent to but out of contact with said web, and means 60 for rigidly supporting said scraper and guard blades.

JAMES M. TRIER.
